UNITED STATES PATENT OFFICE

CURTIS HUSSEY VEEDER, OF HARTFORD, CONNECTICUT, ASSIGNOR, BY MESNE ASSIGNMENTS, TO VEEDER-ROOT INCORPORATED, OF HARTFORD, CONNECTICUT, A CORPORATION OF CONNECTICUT

ODOMETER

Application filed April 4, 1928. Serial No. 267,167.

This invention relates generally to odometers adapted for application to the hubs of vehicle wheels. It has been developed particularly with reference to the application to 5 wire wheels in which the outer or wheel hub shell is detachable from the inner hub, to which the odometer must be attached. For such applications the limitations of size are rather severe and the present invention has 10 for its special object the production of an odometer mechanism which shall meet the limitations of size and shall be reliable and satisfactory in operation.

The invention will be more fully explained 15 hereinafter with reference to the accompanying drawings in which is illustrated an improved embodiment of the invention and in which:

Figure 1 is a view in longitudinal sectional 20 elevation showing a portion of the inner hub of a vehicle wheel with the improved odometer mechanism applied thereto.

Figure 2 is a view of the same in end elevation as seen from the right hand in Figure 1.

Figure 3 is an extended sectional view of 25 the transmitting gearing on a larger scale than that of Figures 1 and 2.

Figure 4 is a view in elevation as seen from 30 the plane indicated by the broken line 4-4 of Figure 3.

Figure 5 is a detail view in section on the plane indicated by the broken line 5-5 of 35 Figure 1, on a larger scale, showing the single toothed ratchet engagement between the main shaft and the eccentric which forms part of the reduction gearing.

Figure 6 is a detail view in section on the plane indicated by the broken line 6-6 of 40 Figure 1.

Figure 7 is a detail view of the dial and 45 wheel arrangement shown diagrammatically in Figure 2.

Figure 8 is a view on the line 8-8 of Figure 9, looking in the direction of the arrows.

Figure 9 is a detail view showing the gears on the shaft carrying the dial h^2 .

Figure 10 is a detail view on the line 10-10 of Figure 11, looking in the direction of the arrows.

Figure 11 is a detail view showing the gears on the shaft carrying the dial h^3 .

In the embodiment of the invention represented in the drawings the odometer a is shown as threaded into the inner hub b of the vehicle wheel. The non-rotating axle c is shown as carrying an arm c^1 arranged for coaction in the usual manner with the arm d of the odometer mechanism to hold the arm d from rotation, so that the odometer mechanism shall be actuated through the rotation of the casing a , the inner hub and the wheel of the vehicle. The hub d^1 of the arm d is supported in a ball bearing d^2 which is carried by a relatively stationary internal gear e held in place against the plate e^3 of a supporting frame e^1 of the odometer mechanism by a ring e^2 threaded into the casing a . This internal gear e , it will be observed, rotates with the wheel and is engaged by one of a pair of compound eccentric gears f, f^1 through which motion is imparted to an internal gear g . The latter, through an Oldham coupling g^1 , imparts motion to the main shaft h , which may be journaled in a hub e^{20} on plate e^3 . The shaft h , through a gear i , drives the first of the odometer dials indicated at h^2, h^3 , etc. Motion is transmitted from one dial to the next in order through transmitting gearing of usual character, indicated at i^2, i^3 , etc., in Figure 3. These dials, as shown in Figure 2, are arranged about the axis of the odometer, the figures on the dials being read through sight openings k^1 in a dial plate k which is held in position by a spring ring k^2 . The compound eccentric gears f, f^1 are carried by an eccentric l which is loose on the hub d^1 . A shaft d^3 is formed with a disk upon which a gear g is journaled, shaft d^3 and hub d^1 being

separate elements to enable the shaft and

disk to be inserted through the eccentric l . In this manner, the shaft d^3 serves as a centering stud. A spring-pressed pawl or dog l^1 , having a single ratchet tooth d^4 , is carried by the eccentric for engagement with the hub d^1 upon forward motion of the wheel. When the eccentric is thus held against rotation, the compound gears f and f^1 , which are driven by gear e rotating with the wheel, are caused to move about the eccentric, to impart reduced motion to gear g , and thence to shaft h . It will be seen that when the pawl rides idly over the single toothed ratchet d^4 when the vehicle is driven backward, the gear g will not be caused to rotate and the odometer mechanism will register only when the vehicle is driven forward.

It will be understood that while the odometer mechanism is in fact actuated by the rotation of the odometer as a whole with respect to the hub d^1 and the shaft c , the effect is the same as if the odometer were held stationary and the shaft c and its appurtenances were rotated.

It will be observed that the dials h^2 , h^3 etc., and the transmitting gearing i^2 , i^3 etc., are supported on spindles e^{12} which are secured at one end in the plate e^3 of the supporting frame e^1 , e^3 , and at the other end in the dial plate h , through the sight openings k^1 in which the dials may be read. The dials are thus supported in a compact circular group about the axis of the odometer.

On movement of the vehicle wheel, shaft h through gear i drives gear i^1 continuously (see especially Figures 7 to 11). On the shaft which carries gear i^1 there is mounted a single toothed gear i^{12} which drives a ten toothed gear i^{22} on the next shaft, thus effecting a ten to 1 reduction in motion between adjacent shafts. The shaft which carries the gear i^{22} is provided with a single toothed gear i^{23} for driving ten toothed gear i^{33} on the next shaft. Locking wheels i^{11} , i^{21} , i^{31} , etc. are mounted on the respective shafts to prevent overrunning and backlash. Gears i^{33} , i^{44} , i^{55} and i^{66} are each driven from the respective preceding shafts by mechanism exactly like that just described except for the relative positions of the gears on the shafts as shown in Figure 3. In as much as ten to one reduction gearing between shafts is well known, the present construction will not be further described.

It will be understood that various details in construction and arrangement may be made to suit different conditions of use, and except as pointed out in the accompanying claim the invention is not restricted to the particular construction shown and described herein.

I claim as my invention:

In an odometer having a casing and a series of dials and transmitting gears supported by a frame and spaced circumferen-

tially about the axis of the odometer, the combination of a gear secured within the casing, a driving member supported by said gear, a supporting frame mounted within the casing, a main shaft supported by the frame in alignment with the driving member and mounted for rotation independently thereof, and means including said main shaft to transmit motion from the driving member to the dials and the transmitting gears.

This specification signed this 30th day of March A. D. 1928.
